UNITED STATES PATENT OFFICE.

NORMAN C. THACKERAY, OF PAWTUCKET, RHODE ISLAND, ASSIGNOR TO IMPERIAL PRINTING & FINISHING CO., OF PAWTUCKET, RHODE ISLAND, A CORPORATION OF RHODE ISLAND.

FABRIC-PRINTING MACHINE.

Application filed March 9, 1925. Serial No. 14,236.

To all whom it may concern:

Be it known that I, NORMAN C. THACKERAY, a citizen of the United States, residing at 278 Prospect St., Pawtucket, in the county of Providence and State of Rhode Island, have invented certain new and useful Improvements in Fabric-Printing Machines, of which the following is a specification.

My invention relates to printing machines 10 employing a stencil for use in printing designs on textiles, paper or other fabrics.

In prior machines of this type color has been fed on to the stencil from a reservoir and has been usually spread or "buttered" 15 through the stencil by a resilient doctor blade. The chief object of my invention is to substitute for these two elements a combination reservoir and doctor blade.

My invention is particularly adapted for 20 multi-color printing, especially to impregnate upon the fabric a plurality of dots or designs of different colors. The dots or designs are so beautifully impregnated on to the fabric that they appear like silk embroidery.

I am aware that a plurality of colors have been sprayed onto a textile fabric through a stencil by means of compressed air through nozzles. I am also aware that a machine 30 substantially identical to the machine of the applicant has been employed for printing two colors wherein the stencil has been provided with recesses to receive one color, the other color being printed as usual through 35 holes in the stencil but so far as I am aware no one has printed textile fabrics by feeding by gravity alone a plurality of colors from a plurality of reservoirs containing different color solutions through a moving 40 perforated stencil on to the upper surface of a moving fabric which process is a further object of my invention.

I am also aware that block stencils for hand printing have been employed having 45 a plurality of reservoirs therein and I am also aware that colors have been led to the stencils through tubes but so far as I am aware no one has provided a suitable printing machine of the stencil type for multi-color printing of fabrics in quantities.

A further object of my invention is to provide a combination doctor blade and reservoir wherein the different reservoirs are readily detachable and which are adapted to

have added any number of separate reservoirs to print the desired number of colors.

These and such other objects of my invention as may hereinafter appear will be best understood from a description of the accompanying drawings which illustrate one embodiment thereof.

In the drawings, Fig. 1 is a side elevation of a printing machine of the stencil type made in accordance with my invention.

Fig. 2 is a fragmentary plan view of the 65 same, a portion of the stencil being broken away to show the location of the combination reservoir and doctor blade.

Fig. 3 is a plan view of the combination reservoir and doctor blade. 70

Fig. 4 is a side elevation of the combination reservoir and doctor blade.

Fig. 5 is an inverted plan view of a portion of the combination reservoir and doctor blade. 75

Fig. 6 is a cross sectional view of the combination reservoir and doctor blade taken along the line 6-6 of Fig. 4.

Fig. 7 is a plan view of a portion of the stencil having a design cut therein. 80

Fig. 8 is a plan view of a portion of a multi-color dotted fabric produced by my invention.

Like characters of reference indicate like parts throughout the drawings. The printing machine shown in Figs. 1 and 2 is constructed exactly in accordance with Patent #550,537 issued Nov. 26, 1895 to Samuel Holt Sharp for fabric printing machines with the exception as heretofore explained 90 that I substitute a combination multi-color reservoir and doctor blade for his two separate elements the reservoir and the doctor blade and adapt his type of machine for use in multi-color printing, and therefore reference is hereby made to said patent for details of construction of the printing machine not shown in the present drawings. The machine comprises the two frames 10 and 11 firmly secured together at a suitable distance by the bolts 12. On the top of these frames are secured bearings 14 in which is mounted the shaft 18 containing the roller 20 adapted to be rotated by the main drive shaft of the machine (not shown). At the feeding end of the machine the frames 10 and 11 are provided with the parallel horizontal slides 22 and 24 on

which are mounted the saddles 26 and 28 carrying bearings 30 and 32 in which is mounted the shaft 34 having the roller 36 fixed thereon, also driven by the main drive shaft. Around the rollers 36 and 20 is carried an endless preferably metallic pattern sheet or stencil 38 which can be tightened or slackened at will by moving the saddles 26 and 28 which support the roller 36, which thus can be caused to advance and recede from the roller 20 by means of screws which are arranged to be turned simultaneously in nuts fixed to the saddles 26 and 28, mitre wheels 40 and 42 fixed on the outwardly projecting ends of the screws and gearing into the mitre wheels 44 and 46 respectively carried on the cross shaft 48 which is carried on the bearings 50 and 52 on the frames 10 and 11 and is provided with the hand wheel 54.

I mount my combination doctor blade and reservoir 56 which will be described in detail later between the upper and lower runs or layers of the endless pattern sheet 38 and also between the rollers 20 and 36 on the upper ends of the frames 10 and 11 respectively. Immediately under the combination reservoir and doctor blade 56 are arranged in the frames 10 and 11 the parallel vertical guides 58 in which are adapted to slide the bearings 60 carrying the shaft 62 on which is fixed the rotary presser or pressing cylinder 64. This cylinder is adapted to be rotated in a suitable manner by the main drive shaft of the machine. The rotary presser 64 is adapted to be moved towards and away from the combination reservoir and doctor blade 56 by means of the eccentrics 66 which are fixed on a cross shaft 68 mounted in bearings 70 in the frames 10 and 11 and which bear simultaneously against projections 72 on the portions 60^a of the sliding bearings 60. On the cross shaft 68 is secured a worm wheel 74 adapted to be rotated by a worm 76 carried between bearings in a bracket 78 mounted for this purpose on the frame 11 of the machine and fixed to a shaft 80 provided with a hand wheel 82. By rotation of the hand wheel 82 it is obvious that the rotary cylinder 64 may be raised and lowered in and out of contact with the endless stencil 38 and the combination doctor blade and reservoir 56. Instead of having the combination doctor blade and reservoir fixed and the presser move it is obvious that these parts may be reversed without departing from my invention.

Mounted in suitable brackets at the front end of the machine is the shaft 84 on which is mounted the roller 86. Around the peripheries of the rotary presser 14 and the roller 86 is passed an endless band 88 hereinafter referred to as a blanket composed preferably of woven flexible material or of

india rubber. In order to enable the necessary tension to be produced in this blanket the cross shaft 84 is mounted in slideable bearings (not shown) adapted to be moved simultaneously outwards from the rotary presser 64 by means of a threaded connection with horizontally slideable rods (not shown), revolvable by threaded engagement with the cross shaft 89 having the hand wheel 90 thereon. In this manner may the roller 86 by turning of the hand wheel 90 be moved horizontally away from the rotary presser 64 to give added tension in the blanket 88.

At the feeding end of the machine is also preferably provided a tension arrangement to regulate the feeding of the fabric into the machine. For this purpose there are secured to the frames 10 and 11 the brackets 92 provided with bearings at their outer ends. On a shaft 94 mounted on these bearings are fixed the double arm levers 96 which are respectively furnished at their ends with bearings in which are mounted the shafts 98 provided with rollers 100 adapted to be rotated about the axis of the shaft 94 by means of a worm wheel 102 fixed to said shaft and geared with a worm 104 on the vertical shaft 106 mounted in a suitable bearing on the bracket 92 and provided with the hand wheel 108. An additional roller 110 may be mounted in bearings on the underside of the brackets 92 which serves in connection with the rollers 100 as a brake for the fabric 112 which is led around the rollers and through the machine as indicated in dotted lines. The fabric 112 after passing between the stencil and blanket is led out in open form to become available for the next step in the process, usually a drying.

Having described in some detail a machine constructed in accordance with the Sharp Patent #550,537 I will now explain in further detail the preferred construction of my combination reservoir and doctor blade which I attach to said machine preferably for multi-color printing and which is shown in detail in Figs. 3-6. This is preferably provided with a frame 114 which comprises the end pieces 116 having the central upstanding portions 118 provided with the longitudinal bolt holes 120 and the base portions 122 provided with the oppositely projecting web portions 124 provided with suitable bolt holes 126 for attachment thereto to the upper ends of the frames 10 and 11, said end pieces 116 being preferably provided at the inner ends with the shoulders 128 for a purpose to be described, and the side pieces 129 adapted to be detachably secured to the sides of the upstanding portions 118 of the end plates 116 by means of the bolts 130. I employ the term "inner" and "outer" with reference to the longitudinal centre of the

machine. Though as stated a combination reservoir and doctor blade containing only one reservoir is within the scope of my invention, it preferably contains a plurality of 5 reservoirs 132 for multi-color printing. These reservoirs 132 are adapted to be detachably mounted within the frame 114. These each preferably individually comprise integral combination base and end plates 10 134 having the base portions 136 extending transversely of the machine provided with the transverse downwardly grooved portions 138 on the upper surface thereof and the integral end portions 140 projecting upwardly 15 from each end of the base thereof. The base portions 136 are adapted to rest on the shoulders 128 of the end pieces 116 of the frame 114, and the sides of the base portions 136 are preferably provided with the 20 shoulders 142 in the sides thereof. I provide two detachable side plates 144 for each reservoir 132, the lower ends of which are adapted to be secured within the shoulders 142 of the upstanding sides 139 of the base portions 136 by means of the screws 146. It is obvious that each reservoir 132 is assembled separately and then laid on the shoulders 128 of the bases 122 of the pieces 116 of the frame. To secure said separate 25 reservoirs 132 from vertical displacement by the pressure of the rotary cylinder 64 underneath I suitably secure the locking plates 148 by means of the bolts 150 in the upper surface of the upstanding portions 118 of the end pieces 116 of the frame 114, the inner edges 152 of said locking plates overlapping the upper edges of the reservoir side plates 144 and the upper edges of the end portions 140 of the combination base and 30 end plates 134. Said reservoir 132, is preferably provided with a doctor blade 154 projecting below the base of the frame 114. In my preferred embodiment I extend the 35 central base plate 134^a downwardly to form the integral doctor blade 154 projecting downwardly below the plane of said other base plates. Said doctor blade 154 is provided with a plurality of orifices 156 arranged transversely thereof, and is provided 40 with the ducts 158 leading directly from the central reservoir 132^a, the ducts 160 leading obliquely downwardly from one side thereof and the ducts 162 leading obliquely downwardly from the opposite side thereof alternately to said orifices 156. The base plates 45 of the outer reservoirs 132^b and 132^c are provided with the ducts 164 and 166 leading obliquely centrally towards the doctor blade 154 adapted to register with the alternate 50 oblique respective ducts 160 and 162 of the doctor blade 154. The doctor blade 154 and base plates 134 of the reservoirs are preferably constructed of brass so as to have an even wearing surface.

The endless metallic stencil 38 used in this

machine is constructed from metal of any suitable width and thickness and through the thickness of which is cut or engraved the pattern or design desired to be produced on the fabric. This sheet is bent into the 70 form of a cylinder causing one end of it to overlap the other for a short distance and the two ends are then soldered or brazed together, the edges and surface being then reduced in thickness until the joint is of the

same thickness as the remainder of the sheet. I employ the word longitudinal in reference to the course the fabric takes in passage through the machine and the word "transverse" at right angles thereto.

The operation of my invention is obvious from the above description. The fabric 112 to be printed is first passed over the roller 110 and rollers 100 of the tension arrangement and then on to the blanket 88. It then 85

passes under the stencil 38, the surface speed of which is equal to that of the blanket and on approaching the combination reservoir and doctor blade 56 the presser 64 begins to bear thereon, increasing in intensity until 90

the fabric reaches and passes thereunder. The effect of this pressure exerted by the rotary presser 64 is to cause the fabric 112 to be forced in the particular holes 39 in the stencil 38 so as to close them and prevent 95

any of the printing composition from passing therethrough. The printing composition which may contain pigments in a liquid or semi-liquid carrier is then fed from the reservoirs 132, the different colors being 100

simultaneously fed through different orifices 156 upon the upper side of the stencil 38, the fabric receiving certain amounts of different colored compositions which by the pressure exerted by the rotary presser 64 105

against the doctor blade 154 are thereby forced into the fabric. By this means clearly distinguishing and permanent impressions are produced on to the fabric. The fabric 112 having passed the doctor blade 110

154 immediately begins to leave the stencil 38 thus preventing the designs or impressions from becoming blurred and is then led on to the next step in the process.

I have shown in Fig. 8 a fabric 112 containing designs of different colors 160 printed by my process from the stencil 38 shown in Fig. 7, the designs having the appearance of beautiful silk embroidery.

It is understood that my invention is not limited to the specific apparatus or processes described and shown and that various deviations may be made therefrom without departing from the spirit and scope of the appended claims.

What I claim as new and desire to secure as Letters Patent is:

1. The process of printing fabrics which comprises feeding by gravity alone a plurality of colors from a plurality of different

color reservoirs simultaneously through a perforated stencil on to the upper surface of a moving fabric.

2. The process of printing fabrics which comprise feeding by gravity alone a plurality of colors from a plurality of different color reservoirs simultaneously through a perforated stencil on to a moving fabric.

3. In a fabric printing machine of the stencil type, the combination of a frame, an endless moving stencil mounted thereon having design perforations therein, a rotary presser mounted on said frame underneath said stencil to coat with said stencil, a combination doctor blade and multicolor reservoir mounted on said frame above the lower layer of said stencil, having a plurality of orifices in the stencil contacting end thereof extending substantially vertically downwards, an endless blanket moving over said rotary presser and means to draw the fabric in open form between said blanket and stencil, substantially at right angles to the stencil contacting end of said combination reservoir and doctor blade.

4. In a fabric printing machine of the stencil type, the combination of a frame, an endless moving stencil mounted thereon having design perforations therein, a rotary presser mounted on said frame underneath said stencil to coat with said stencil, a combination doctor blade and multi-color reservoir mounted on said frame above the lower layer of said stencil having a plurality of orifices in the stencil contacting end thereof extending substantially vertically downwards and means to draw the fabric in open form between said presser and stencil substantially at right angles to the stencil contacting end of said combination reservoir and doctor blade.

5. In a fabric printing machine of the stencil type, the combination of a frame, an endless moving stencil mounted thereon having design perforations therein, a rotary presser mounted on said frame to coat with said stencil, a combination doctor blade and multi-color reservoir mounted on said frame, having a plurality of orifices in the stencil contacting end thereof extending substantially vertically downwards, an endless blanket moving over said rotary presser and means to draw the fabric in open form between said blanket and stencil substantially at right angles to the stencil contacting end of said combination reservoir and doctor blade.

6. In a fabric printing machine of the stencil type, the combination of a frame, an endless moving stencil mounted thereon having design perforations therein, a rotary presser mounted on said frame underneath said stencil to coat with said stencil, a combination doctor blade and reservoir mounted on said frame above the lower

layer of said stencil having a plurality of orifices in the stencil contacting end thereof extending substantially vertically downwards, an endless blanket moving over said rotary presser and means to draw the fabric in open form between said blanket and stencil substantially at right angles with the stencil contacting end of said combination reservoir and doctor blade.

7. In a fabric printing machine of the stencil type, the combination of a frame, an endless moving stencil mounted thereon having design perforations therein, a rotary presser mounted on said frame to coat with said stencil, a combination doctor blade and multicolor reservoir mounted on said frame having a plurality of orifices in the stencil contacting end thereof extending substantially vertically downwards and means to draw the fabric in open form between said presser and stencil substantially at right angles to the stencil contacting end of said combination reservoir and doctor blade.

8. In a fabric printing machine of the stencil type, the combination of a frame, an endless moving stencil mounted thereon having design perforations therein, a rotary presser mounted on said frame underneath said stencil to coat with said stencil, a combination doctor blade and reservoir mounted on said frame above the lower layer of said stencil having a plurality of orifices in the stencil contacting end thereof extending substantially vertically downwards, and means to draw the fabric in open form between said presser and stencil substantially at right angles to the stencil contacting end of said combination reservoir and doctor blade.

9. In a fabric printing machine of the stencil type, the combination of a frame, an endless moving stencil mounted thereon having design perforations therein, a rotary presser mounted on said frame to coat with said stencil, a combination doctor blade and reservoir mounted on said frame having a plurality of orifices in the stencil contacting end thereof extending substantially vertically downwards, an endless blanket moving over said rotary presser and means to draw the fabric in open form between said blanket and stencil substantially at right angles to the stencil contacting end of said combination reservoir and doctor blade.

10. In a fabric printing machine of the stencil type, the combination of a frame, an endless moving stencil mounted thereon, having design perforations therein, a rotary presser mounted on said frame to coat with said stencil, a combination doctor blade and reservoir mounted on said frame having a plurality of orifices in the stencil contacting end thereof extending substantially vertically downwards and means to draw the fabric in open form between said blanket and stencil substantially at right angles to the stencil contacting end of said combination reservoir and doctor blade.

machine. Though as stated a combination reservoir and doctor blade containing only one reservoir is within the scope of my invention, it preferably contains a plurality of 5 reservoirs 132 for multi-color printing. These reservoirs 132 are adapted to be detachably mounted within the frame 114. These each preferably individually comprise integral combination base and end plates 10 134 having the base portions 136 extending transversely of the machine provided with the transverse downwardly grooved portions 138 on the upper surface thereof and the integral end portions 140 projecting upwardly 15 from each end of the base thereof. The base portions 136 are adapted to rest on the shoulders 128 of the end pieces 116 of the frame 114, and the sides of the base portions 136 are preferably provided with the 20 shoulders 142 in the sides thereof. I provide two detachable side plates 144 for each reservoir 132, the lower ends of which are adapted to be secured within the shoulders 142 of the upstanding sides 139 of the base portions 136 by means of the screws 146. It is obvious that each reservoir 132 is assembled separately and then laid on the shoulders 128 of the bases 122 of the pieces 25 116 of the frame. To secure said separate reservoirs 132 from vertical displacement by the pressure of the rotary cylinder 64 underneath I suitably secure the locking plates 148 by means of the bolts 150 in the upper surface of the upstanding portions 118 of 30 the end pieces 116 of the frame 114, the inner edges 152 of said locking plates overlapping the upper edges of the reservoir side plates 144 and the upper edges of the end portions 140 of the combination base and 35 end plates 134. Said reservoir 132, is preferably provided with a doctor blade 154 projecting below the base of the frame 114. In my preferred embodiment I extend the 40 central base plate 134a downwardly to form the integral doctor blade 154 projecting downwardly below the plane of said other base plates. Said doctor blade 154 is provided with a plurality of orifices 156 arranged transversely thereof, and is provided 45 with the ducts 158 leading directly from the central reservoir 132a, the ducts 160 leading obliquely downwardly from one side thereof and the ducts 162 leading obliquely downwardly from the opposite side thereof alternately to said orifices 156. The base plates 50 of the outer reservoirs 132b and 132c are provided with the ducts 164 and 166 leading obliquely centrally towards the doctor blade 154 adapted to register with the alternate oblique respective ducts 160 and 162 of the 55 doctor blade 154. The doctor blade 154 and base plates 134 of the reservoirs are preferably constructed of brass so as to have an even wearing surface.

The endless metallic stencil 38 used in this

machine is constructed from metal of any suitable width and thickness and through the thickness of which is cut or engraved the pattern or design desired to be produced on the fabric. This sheet is bent into the 70 form of a cylinder causing one end of it to overlap the other for a short distance and the two ends are then soldered or brazed together, the edges and surface being then reduced in thickness until the joint is of the 75 same thickness as the remainder of the sheet. I employ the word longitudinal in reference to the course the fabric takes in passage through the machine and the word "transverse" at right angles thereto.

The operation of my invention is obvious from the above description. The fabric 112 to be printed is first passed over the roller 110 and rollers 100 of the tension arrangement and then on to the blanket 88. It then 80 passes under the stencil 38, the surface speed of which is equal to that of the blanket and on approaching the combination reservoir and doctor blade 56 the presser 64 begins to bear thereon, increasing in intensity until 85 the fabric reaches and passes thereunder. The effect of this pressure exerted by the rotary presser 64 is to cause the fabric 112 to be forced in the particular holes 39 in the stencil 38 so as to close them and prevent 90 any of the printing composition from passing therethrough. The printing composition which may contain pigments in a liquid or semi-liquid carrier is then fed from the reservoirs 132, the different colors being 95 simultaneously fed through different orifices 156 upon the upper side of the stencil 38, the fabric receiving certain amounts of different colored compositions which by the 100 pressure exerted by the rotary presser 64 against the doctor blade 154 are thereby forced into the fabric. By this means clearly distinguishing and permanent impressions are produced on to the fabric. The 105 fabric 112 having passed the doctor blade 154 immediately begins to leave the stencil 38 thus preventing the designs or impressions from becoming blurred and is then led on to the next step in the process.

I have shown in Fig. 8 a fabric 112 containing designs of different colors 160 printed by my process from the stencil 38 shown in Fig. 7, the designs having the appearance of beautiful silk embroidery.

It is understood that my invention is not limited to the specific apparatus or processes described and shown and that various deviations may be made therefrom without departing from the spirit and scope of the appended claims.

What I claim as new and desire to secure as Letters Patent is:

1. The process of printing fabrics which comprises feeding by gravity alone a plurality of colors from a plurality of different 130

color reservoirs simultaneously through a perforated stencil on to the upper surface of a moving fabric.

2. The process of printing fabrics which comprise feeding by gravity alone a plurality of colors from a plurality of different color reservoirs simultaneously through a perforated stencil on to a moving fabric.

3. In a fabric printing machine of the 10 stencil type, the combination of a frame, an endless moving stencil mounted thereon having design perforations therein, a rotary presser mounted on said frame underneath said stencil to coat with said stencil, a 15 combination doctor blade and multicolor reservoir mounted on said frame above the lower layer of said stencil, having a plurality of orifices in the stencil contacting end thereof extending substantially vertically downwards, an endless blanket moving over 20 said rotary presser and means to draw the fabric in open form between said blanket and stencil, substantially at right angles to the stencil contacting end of said combination reservoir and doctor blade.

4. In a fabric printing machine of the 25 stencil type, the combination of a frame, an endless moving stencil mounted thereon having design perforations therein, a rotary 30 presser mounted on said frame underneath said stencil to coat with said stencil, a combination doctor blade and multi-color reservoir mounted on said frame above the lower 35 layer of said stencil having a plurality of orifices in the stencil contacting end thereof extending substantially vertically downwards and means to draw the fabric in open form between said presser and stencil substantially 40 at right angles to the stencil contacting end of said combination reservoir and doctor blade.

5. In a fabric printing machine of the 45 stencil type, the combination of a frame, an endless moving stencil mounted thereon having design perforations therein, a rotary 50 presser mounted on said frame to coat with said stencil, a combination doctor blade and multi-color reservoir mounted on said frame, having a plurality of orifices in the 55 stencil contacting end thereof extending substantially vertically downwards, an endless blanket moving over said rotary presser and means to draw the fabric in open form between said blanket and stencil substantially 60 at right angles to the stencil contacting end of said combination reservoir and doctor blade.

6. In a fabric printing machine of the 65 stencil type, the combination of a frame, an endless moving stencil mounted thereon having design perforations therein, a rotary 70 presser mounted on said frame underneath said stencil to coat with said stencil, a combination doctor blade and reservoir 75 mounted on said frame above the lower 80 layer of said stencil having a plurality of orifices in the stencil contacting end thereof extending substantially vertically downwards and means to draw the fabric in open form between said blanket and stencil substantially 85 at right angles to the stencil contacting end of said combination reservoir and doctor blade.

layer of said stencil having a plurality of orifices in the stencil contacting end thereof extending substantially vertically downwards, an endless blanket moving over said rotary presser and means to draw the fabric in open form between said blanket and stencil substantially at right angles with the stencil contacting end of said combination reservoir and doctor blade.

7. In a fabric printing machine of the 90 stencil type, the combination of a frame, an endless moving stencil mounted thereon having design perforations therein, a rotary presser mounted on said frame to coat with said stencil, a combination doctor blade and 95 multicolor reservoir mounted on said frame having a plurality of orifices in the stencil contacting end thereof extending substantially vertically downwards and means to draw the fabric in open form between said 100 presser and stencil substantially at right angles to the stencil contacting end of said combination reservoir and doctor blade.

8. In a fabric printing machine of the 105 stencil type, the combination of a frame, an endless moving stencil mounted thereon having design perforations therein, a rotary presser mounted on said frame underneath said stencil to coat with said stencil, a combination doctor blade and reservoir mounted on said frame above the lower layer of said stencil having a plurality of orifices in the stencil contacting end thereof extending substantially vertically downwards, and means to draw the fabric in open form between said presser and stencil substantially 110 at right angles to the stencil contacting end of said combination reservoir and doctor blade.

9. In a fabric printing machine of the 115 stencil type, the combination of a frame, an endless moving stencil mounted thereon having design perforations therein, a rotary 120 presser mounted on said frame to coat with said stencil, a combination doctor blade and reservoir mounted on said frame having a plurality of orifices in the stencil contacting end thereof extending substantially vertically downwards, an endless blanket moving over said rotary presser and means to draw the fabric in open form between said blanket and stencil substantially 125 at right angles to the stencil contacting end of said combination reservoir and doctor blade.

10. In a fabric printing machine of the 130 stencil type, the combination of a frame, an endless moving stencil mounted thereon, having design perforations therein, a rotary presser mounted on said frame to coat with said stencil, a combination doctor blade and reservoir mounted on said frame having a plurality of orifices in the stencil contacting end thereof extending substantially vertically downwards and means to draw the

fabric in open form between said presser and stencil substantially at right angles to the stencil contacting end of said combination reservoir and doctor blade.

5 11. In a fabric printing machine of the stencil type, the combination of a frame, an endless moving stencil mounted thereon having design perforations therein, a rotary presser mounted on said frame underneath said stencil to coat with said stencil, a combination doctor blade and multicolor reservoir mounted on said frame above the lower layer of said stencil, comprising a frame, a plurality of detachable reservoirs mounted 10 within and extending transversely of said frame adapted to contain a plurality of different colored printing compositions, and a doctor blade projecting integrally centrally from the base of said frame having a plurality of orifices arranged transversely 15 thereof and ducts leading alternately from each reservoir to said orifices, an endless blanket moving over said rotary presser and means to draw the fabric in open form between said blanket and stencil.

20 12. In a fabric printing machine of the stencil type, the combination of a frame, an endless moving stencil mounted thereon having design perforations therein, a rotary presser mounted on said frame underneath said stencil to coat with said stencil, a combination doctor blade and multi-color reservoir mounted on said frame above the lower layer of said stencil, comprising a frame, a plurality of reservoirs mounted 25 within said frame adapted to contain a plurality of different colored printing compositions, a doctor blade projecting from the base of said frame having a plurality of orifices arranged transversely thereof and ducts leading from each reservoir to said orifices, an endless blanket moving over said rotary presser and means to draw the fabric in open form between said blanket and stencil.

30 13. In a fabric printing machine of the stencil type, the combination of a frame, an endless moving stencil mounted thereon having design perforations therein, a rotary presser mounted on said frame underneath said stencil to coat with said stencil, a combination doctor blade and multicolor reservoir mounted on said frame above the lower layer of said stencil, comprising a frame, a plurality of reservoirs mounted within said frame adapted to contain a plurality of different colored printing compositions, a doctor blade projecting from the base of said frame having a plurality of orifices arranged transversely thereof and ducts leading from each reservoir to said orifices, an endless blanket moving over said rotary presser and means to draw the fabric in open form between said blanket and stencil.

35 14. In a fabric printing machine of the

stencil type, the combination of a frame, an endless moving stencil mounted thereon having design perforations therein, a rotary presser mounted on said frame underneath said stencil to coat with said stencil, a combination doctor blade and multicolor reservoir mounted on said frame above the lower layer of said stencil, comprising a frame, a plurality of detachable reservoirs mounted within and extending transversely of said frame adapted to contain a plurality of different colored printing compositions, a doctor blade projecting integrally centrally from the base of said frame having a plurality of orifices arranged transversely thereof and ducts leading from each reservoir to said orifices, an endless blanket moving over said rotary presser and means to draw the fabric in open form between said blanket and stencil. 85

40 15. In a fabric printing machine of the stencil type, the combination of a frame, an endless moving stencil mounted thereon having design perforations therein, a rotary presser mounted on said frame to coat with said stencil, a combination doctor blade and reservoir mounted on said frame, comprising a frame, a reservoir mounted on said frame for containing a printing composition and a doctor blade projecting from the base of said frame having a plurality of orifices arranged transversely thereof and ducts leading from said reservoir to said orifices, an endless blanket moving over said rotary presser and means to draw the fabric in open form between said presser and stencil. 90

45 16. A combination reservoir and doctor blade for fabric printing machines of the stencil type, comprising a frame, a plurality of detachable reservoirs mounted within and extending transversely of said frame adapted to contain a plurality of different colored printing compositions, a doctor blade projecting integrally centrally from the base of said frame having a plurality of orifices arranged transversely thereof and ducts leading alternately from each reservoir to said orifices. 100

50 17. A combination reservoir and doctor blade for fabric printing machines of the stencil type comprising a frame, a plurality of reservoirs mounted within said frame adapted to contain a plurality of different colored printing compositions, a doctor blade projecting from the base of said frame having a plurality of orifices arranged transversely thereof and ducts leading from each reservoir to said orifices. 110

55 18. A combination reservoir and doctor blade for fabric printing machines of the stencil type comprising a frame, a plurality of reservoirs mounted within said frame adapted to contain a plurality of different colored printing compositions, a doctor

- blade projecting from the base of said frame having a plurality of orifices arranged transversely thereof and ducts leading alternately from each reservoir to said orifices. 5
19. A combination reservoir and doctor blade for fabric printing machines of the stencil type comprising a frame, a plurality of detachable reservoirs mounted within 10 and extending transversely of said frame adapted to contain a plurality of different colored printing compositions, a doctor blade projecting integrally centrally from the base of said frame having a plurality of 15 orifices arranged transversely thereof and ducts leading from each reservoir to said orifices.
20. A combination reservoir and doctor blade for fabric printing machines of the stencil type comprising a frame, a reservoir mounted on said frame for containing a printing composition and a doctor blade projecting from the base of said frame having a plurality of orifices arranged transversely thereof and ducts leading from said reservoir to said orifices. 25
21. A combination reservoir and doctor blade for fabric printing machines of the stencil type, comprising an oblong frame 30 having means for attachment to the frame of the printing machine, a plurality of detachable oblong reservoirs mounted within and extending transversely of said frame, each comprising detachable side plates and 35 detachable combination base and end plates having shoulders in the sides thereof to receive said side plates, the central base plate having a portion projecting below the plane of said other base plates having a 40 plurality of orifices arranged transversely thereof and ducts leading alternately downwardly from said central reservoir, obliquely from one side and then obliquely from the other side thereof to said orifices, the base plates of the other reservoirs having ducts leading obliquely centrally thereof to register with said alternate oblique ducts of the central base plate. 45
22. A combination multi-color reservoir and doctor blade for fabric printing machines of the stencil type, comprising a substantially oblong frame comprising end pieces having webs on the base thereof for attachment to the printing machine and shoulders projecting inwardly thereof and 50 side plates secured to the sides thereof, a plurality of oblong reservoirs detachably mounted within and extending transversely of said frame each comprising integral combination base and end plates resting on the shoulders of said frame having downwardly grooved portions on the upper surface of the base thereof and having shoulders in the sides thereof and detachable side plates secured within the shoulders in the sides of 55 said base plates, locking plates secured to the upper ends of said frame end plates overlapping the upper surfaces of the reservoir side plates and combination base and end plates, the central reservoir base plate 60 having a portion projecting downwardly below the plane of said other base plates having a plurality of orifices arranged transversely thereof and ducts in said base plate leading alternately downwardly from 65 said central reservoir obliquely from first one side and then obliquely from the opposite side thereof to said orifices, the base plates of the other reservoirs having ducts leading obliquely centrally thereof to register with said alternate oblique ducts of the central base plate. 70
- In testimony whereof I affix my signature.
NORMAN C. THACKERAY. 75
